UNITED STATES PATENT OFFICE.

LEWIS C. MALTBY, OF WASHINGTON, DISTRICT OF COLUMBIA, ASSIGNOR TO THE STONE STRAW COMPANY, OF WASHINGTON, DISTRICT OF COLUMBIA, A CORPORATION OF NEW JERSEY.

CUT-OFF MECHANISM FOR MACHINES FOR MAKING ARTIFICIAL STRAWS.

1,207,585.

Specification of Letters Patent.

Patented Dec. 5, 1916.

Application filed February 12, 1916. Serial No. 78,058.

To all whom it may concern:

Be it known that I, LEWIS C. MALTBY, a citizen of the United States, residing at Washington, in the District of Columbia, have invented certain new and useful Improvements in Cut-Off Mechanism for Machines for Making Artificial Straws, of which the following is a specification.

My invention relates to an improvement in the cut-off mechanism for machines for making artificial straws, and the fundamental feature of this present invention comprises a reciprocating plunger which carries a section of the straw guide, and which also operates and controls the saw-disk, causing the two to reciprocate together; and in connection with these features there is a rocking frame which carries the disk cutter shaft, and which is swung positively back and forth to cause the disk cutter to cross and re-cross the path of the straw to cut it off into the required predetermined lengths.

In the accompanying drawings: Figure 1 is a plan view; Fig. 2 is a view in side elevation with parts broken away, and the bed or frame of the machine in longitudinal section; Fig. 3 is a view in side elevation showing the rocking frame with the other parts removed, the view being partially in section; Fig. 4 is a section on the line 4—4 of Fig. 2, looking toward the right; Fig. 5 is a section on the line 5—5 of Fig. 2, looking toward the right; and Fig. 6 is a fragmentary view in section of the upper end of the rocking frame.

A, is the bed or frame of the machine, which is cast in any suitable form and dimensions for the purpose and mounted on legs (not shown). A housing 1 is mounted on the bed edge and terminates at the forward end in a plunger-guide 2.

Rotatably mounted within the housing on a shaft 3 is the crank-disk 4, and fitted to a slide within the cross-head guide 2 is the reciprocating cross-head or plunger 5 which is actuated by connecting-rod 6 extending from the wrist-pin 7 on the crank disk 4 to a point 8 in the cross-head or plunger.

To take up for wear in the cross-head or plunger, the plate 9 is adjustably connected with the plunger or cross-head through set-screw 10, their adjacent faces inclined, as at 11, so that when the plate 9 is forced in-

wardly it takes up for wear in the cross-head or cross-head guide, as is readily understood.

The shaft 3 has a miter gear 12 on one end, the teeth of which mesh with a miter gear 13 on the countershaft 14, and the countershaft 14 is supported in bearings 15 in the arms 16 bolted or otherwise secured to one side of the bed. This shaft 14 has a large gear-wheel 17 keyed thereto, and the teeth of this wheel engage the teeth of an intermediate gear 18, which is driven by a pinion 19, on the main drive-shaft 20, from which motion is consequently communicated at a greatly reduced speed in this way from the drive-shaft 20 to the countershaft 14, and through it to the shaft 3 and the reciprocating cross-head or plunger 5.

A rocking frame 21 (shown in Fig. 3) is pivoted by bolts 22, 22, at either end to lugs 23, 23, on the side of the housing 1 (as shown in Figs. 4 and 5), and this rocking frame is oscillated through a connecting-rod 24 extending from the eccentric strap 25 to which it is bolted by nuts 26, 26. This eccentric strap is mounted on the eccentric 27 secured on the counter-shaft 14. A shaft 28, 80 is slidably mounted in the collars 29, 29, at the upper end of the rocking frame 21, and on this shaft the saw-disk 30 is secured.

An arm 31 extends upwardly from the cross-head or plunger 5, and is provided with an elongated slot 32, in the form of an arc, the center of which coincides with the support or center of vibration 22 of the frame 21, and through this slot the shaft 28 which carries the disk cutter 30 extends, (as shown in Figs. 4 and 5) thus admitting of the oscillation of the frame 21 which carries the shaft 28, and the movement of the latter through slot 32. The upper or slotted end of the arm 31 is confined between the hub 33 of the saw-disk and the collar 34 secured on the shaft 28, so that with the reciprocations of the cross-head or plunger the shaft 28 which carries the disk cutter also reciprocates, and with the turning of the eccentric 27 with the rotation of counter-shaft 14, the rocking frame 21 is oscillated to move the disk cutter laterally across and away from the path of the straw.

The straw is fed through stationary and movable straw-guides 35 and 36 respectively,

the former being held on one side of the housing 1 (as shown in Fig. 1), and the latter being carried by an arm 37 projecting out on the opposite side of the cross-head or 5 plunger from the arm 31 (as shown in Figs. 4 and 5).

The shaft 28 is rotated by a belt (not shown) passed over the pulley 40, which pulley is secured to the rotary bearings 41 10 which turn in the left-hand collar 29 on the frame 21 (as shown in Figs. 2 and 6).

To briefly recapitulate, with the driving of the countershaft 14 from the main shaft 20, through the gear-wheels 19, 18, and 17, 15 the shaft 3 is rotated through miter-gears 13, and 12, thus causing the cross-head or plunger 5 to reciprocate in the plunger-guide 2; and with it the rotating shaft 28 which carries the disk cutter 30 in the rock- 20 ing-frame 21, which latter oscillates but does not reciprocate; and also the movable straw-guide section 36; and at the same time, through the rotation of the counter- 25 shaft 14 and eccentric 27 thereon, the rock- ing frame 21, which carries the sliding rotary disk cutter shaft 28, is oscillated once during each revolution of the countershaft, thus causing the disk cutter 30 to cross the 30 path of the straw, which is feeding through the straw-guides 35 and 36, travel with the latter, cut it, and immediately recede from its path.

I claim:

1. The combination of a machine-bed or 35 frame, a reciprocating cross-head having arms which extend in opposite directions through slots in the frame, one arm carrying a straw guide and the other arm extending upward having a horizontally disposed 40 elongated slot, a rocking frame, and a disk cutter shaft slidably mounted in said frame and extending through the elongated slot of the arm on the cross-head, said slidable shaft having a disk cutter secured thereon on one 45 side of said arm, a collar secured on the shaft, on the other side of the arm, whereby

the shaft is reciprocated with the cross-head, and means for actuating these several parts.

2. The combination of a machine-bed or frame, a cross-head guide formed therein, a 50 cross-head fitted thereto, a plate adjustably secured to the cross-head and located between one side of the guide and the cross-head for taking up the wear of the cross-head, arms extending in opposite directions 55 from the cross-head, one carrying a straw guide and the other a slotted arm, a rocking frame and shaft slidably mounted in said frame and carrying a disk cutter, said shaft passed through the slot of the arm with the 60 disk cutter adjacent thereto, a collar secured on the shaft on the other side of the slotted arm, means for reciprocating the cross-head, straw guide and slidable shaft, and means for rocking the rocking frame with the sliding shaft and disk cutter.

3. The combination with a machine-bed or frame, a rocking frame pivotally connected therewith, a reciprocating plunger or cross-head, a main drive-shaft, a counter- 70 shaft driven thereby, said countershaft having a miter gear and an eccentric thereon, a cross-shaft having a miter gear intermeshed with the miter gear on the countershaft, a crank disk carried on said 75 cross-shaft, a connecting rod extending from the crank-disk to the plunger or cross-head, an eccentric strap around the eccentric and connecting-rod extending therefrom to the rocking-frame, two arms extending from the 80 cross-head or plunger, one having an elongated slot, and the other carrying a straw guide, and a shaft rotatably and slidably supported by the rocking frame and extending through the slot in the slotted arm on 85 the plunger or cross-head, said shaft carrying a disk cutter which is adapted to travel with and cross the path of the straw to be cut.

In testimony whereof I affix my signature. 90

LEWIS C. MALTBY.
